(57) **CLAIM**

I claim ornamental design of a keychain configured as a whale, substantially as shown in the drawings.

DESCRIPTION

FIG. 1 is a view of the left side of a keychain configured as a whale of the present invention, the right side being a mirror image thereof;

FIG. 2 is a rear view of a keychain configured as a whale of the present invention;

FIG. 3 is a front view of a keychain configured as a whale of the present invention;

FIG. 4 is a bottom view of a keychain configured as a whale of the present invention; and,

FIG. 5 is a top view of a keychain configured as a whale of the present invention.
